A. VARAUD

CLOCKWORK OPERATED MECHANICAL FUSE FOR ARTILLERY PROJECTILES

Original Filed May 13, 1924

Inventor

André Varaud

By his attorney

UNITED STATES PATENT OFFICE.

ANDRÉ VARAUD, OF GENEVA, SWITZERLAND.

CLOCKWORK-OPERATED MECHANICAL FUSE FOR ARTILLERY PROJECTILES.

Original application filed May 13, 1924, Serial No. 712,960, and in Switzerland August 2, 1924. Divided and this application filed June 26, 1925. Serial No. 39,699.

The invention relates to clockwork mechanical fuses for artillery projectiles of the type in which the release of the striker is controlled by a rotary member, the angular position of which can be set prior to firing and which during its trajectory is driven in a direction inversely its setting by means of the clockwork. It refers more particularly to a ratchet mechanism used in such fuses for, on the one part, to prevent the retrogradation of the motive power stored up in the driving spring of the clockwork, and on the other part, for adjusting exactly prior to firing the setting position given to the rotary member controlling the release of the striker.

In known fuses of this kind this ratchet mechanism does not permit of obtaining a large number of rigorously determined different angular setting positions if at the same time a relatively small diameter of the fuse is maintained.

The ratchet mechanism which is the object of the present invention eliminates this inconvenience and makes it possible to obtain from 50 to 1000 different well determined locking positions by each winding turn without increasing the transverse dimensions of the fuse with regard to the standards admitted by the actual requirements of the artillery.

This ratchet or locking mechanism is characterized by laterally arranged teeth, and is keyed to the main-shaft, and by an axially movable crown pawl with opposed laterally arranged teeth and also having internal teeth which serve, on the one hand, for immobilizing it angularly during the winding and the simultaneous setting of the fuse and as long as the wound-up clockwork is not started and on the other hand for transmitting the driving power to the gear train of the clockwork during the operation of the latter.

The annexed drawing represents by way of example an embodiment of the object of the invention.

Fig. 1 is a side elevation,

Fig. 2 a plan view

Fig. 3 a cross section along the line 3—3 of Fig. 2, and the

Figs. 4 and 5 are detail plan views showing separately the ratchet disk seen from above and the crown pawl seen from below.

The ratchet disk 1 of the locking mech-

anism is keyed to the upper portion of the driving shaft 2 carrying the barrel-centre (not shown) of the main spring of the clockwork. This ratchet disk 1 is provided at its periphery with a border extending 60 outwardly therefrom. In the upper part of this border are radially cut the gullet teeth 3. The dimensions of these teeth 3 with regard to the diameter of the ratchet disk 1 are very small, a fact which permits 65 of having a comparatively large number of teeth, for instance 100 of them on a ratchet of a diameter of 20 mm.

The crown pawl 4 is also provided at its periphery with a border projecting towards 70 the inner part of the fuse and in which border the radial gullet teeth 5 are cut which correspond to the teeth 3 of the ratchet 1.

This crown pawl 4 is freely mounted on the ratchet disk 1 inside a ring 6 fixed to 75 the periphery of the ratchet disk 1 by means of screws 7 and having extension or flaps 8 operating as springs which are bent over the crown pawl 4 so as to bear elastically at equidistant points in order to normally 80 hold the teeth 3 and 5 in mesh.

The crown pawl 4 is also provided with internal gear teeth 9 in constant mesh with a pinion 10 keyed on the inner extremity of a shaft 11. This latter, during the whole 85 period of winding the main spring and as long as the clockwork has not been started, is prevented from rotating by any convenient means. It therefore locks the crown pawl 4 in its angular position which 90 again holds the ratchet disk 1 stationary or in other words prevents the retrogradation of the power stored up in the shaft 2.

During the storage of this power, the withdrawal of the teeth 5 of the crown pawl 95 4 in order to pass over the teeth 3 of the ratchet disk 1 between two succeeding locking positions, is effected parallel to the shafts 2 and 11 against the action of the bent over flaps 8 performing the function 100 of retaining springs.

Means (not shown in the drawing) are provided for liberating the shaft 11 and in so doing to start the clockwork as soon as this locking engagement is no longer a necessity. At this moment the mechanism works like an ordinary clutch with gullet teeth for transmitting at a multiplied speed the motive power transmitted through the shaft 11 to the (not shown) gear train of 110

the clockwork, the last moving member of which comprises the escapement wheel of the regulating device of the fuse.

The efficiency of the locking realized by means of the teeth 5 of the crown pawl 4 whilst the shaft 11 remains immobilized is assured regardless of the extremely reduced dimensions of said teeth, owing to their large number.

10 In the space left free between the crown pawl 4 and the ratchet disk 1 at the interiorly of the teeth 3 and 5 are accommodated two winding pinions 12 and 13, the latter of which is keyed on the lower extremity of the winding up driving shaft 14 and the former one on the outer end of the shaft 2.

It is not necessary that the teeth 3 and 5 are the same in number. One out of two of them might be left out, for instance the teeth 5 of the crown pawl might be only one half of the number of the teeth 3 of the ratchet disk without interfering with the security of the locking. Of course the distance between the teeth 5 must be made in such a manner as to correspond to the width of a tooth 3 of ratchet disk 1.

What I claim is:

1. In a clockwork operated mechanical fuse, a drive shaft, a ratchet disk mounted thereon and having a series of peripheral laterally extending teeth, an axially movable crown pawl also having a series of peripheral laterally extending teeth for engagement with the laterally extending teeth of the said ratchet disk, and means for yieldingly maintaining the said series of laterally extending teeth in mesh with one another whereby the laterally extending teeth of the ratchet disk slide over the laterally extending teeth of the said crown pawl during the winding and setting of the fuse and the said crown pawl is driven by the said ratchet disk during the operation of the clockwork.

2. In a clockwork operated mechanical fuse, a drive shaft, a ratchet disk mounted thereon and having a series of peripheral laterally extending teeth, an axially movable crown pawl also having a series of peripheral laterally extending teeth for engagement with the laterally extending teeth of the ratchet disk, and spring members bearing yieldingly on the said crown pawl for maintaining the series of laterally extending teeth thereon in mesh with the series of laterally extending teeth of the ratchet disk whereby the laterally extending teeth of the ratchet disk slide over the laterally extending teeth of the said crown pawl during the winding and setting of the fuse and the said crown pawl is driven by the said ratchet disk during the operation of the clockwork.

3. In a clockwork operated mechanical

fuse, a drive shaft, a ratchet disk secured thereto and having a series of peripheral laterally extending teeth, a ring surrounding the said ratchet disk, a crown piece within the said ring and also having a series of peripheral laterally extending teeth, and a plurality of spring members secured to the said ring and adapted to yieldingly engage the said crown pawl to maintain the laterally extending teeth thereof in mesh with the laterally extending teeth of the ratchet disk whereby the laterally extending teeth of the ratchet disk slide over the laterally extending teeth of the said crown pawl during the winding and setting of the fuse and the said crown pawl is driven by the said ratchet disk during the operation of the clockwork.

4. In a clockwork operated mechanical fuse, a drive shaft, a winding shaft, a ratchet disk secured on the drive shaft and having a series of peripheral laterally extending teeth, pinions connecting the said winding shaft and drive shaft, a crown pawl also having a series of peripheral laterally extending teeth for engagement with the said series of laterally extending teeth of the ratchet disk, and means for yieldingly maintaining the said series of laterally extending teeth in mesh with one another whereby the laterally extending teeth of the ratchet disk slide over the laterally extending teeth of the said crown pawl during the winding and setting of the fuse and the said crown pawl is driven by the said ratchet disk during the operation of the clockwork.

5. In a clockwork operated mechanical fuse, a drive shaft, a winding shaft, a ratchet disk mounted on the drive shaft and having a series of peripheral laterally extending teeth, means for connecting the winding shaft and the drive shaft for turning the latter from the former, a crown pawl also having a series of peripheral laterally extending teeth for engagement with the laterally extending teeth of the ratchet disk, a clockwork shaft, means for driving the clockwork shaft from the said crown pawl, and means for yieldingly maintaining the said series of laterally extending teeth in mesh with one another whereby the laterally extending teeth of the ratchet disk slide over the laterally extending teeth of the said crown pawl during the winding and setting of the fuse and the said crown pawl is driven by the said ratchet disk during the operation of the clockwork.

6. In a clockwork operated mechanical fuse, a drive shaft, a ratchet disk secured to the drive shaft and having a series of peripheral laterally extending teeth, a winding shaft, a pinion thereon, a pinion on the drive shaft meshing with the pinion on the winding shaft, a crown pawl having

- a series of peripheral laterally extending teeth adapted to engage with the said series of laterally extending teeth on the ratchet disk and also a series of internal gear teeth, 5 a clockwork shaft, a pinion thereon adapted to mesh with the internal gear teeth of the crown pawl, a ring surrounding the said ratchet disk and within which the said 30 crown pawl lies so as to be guided thereby, and a plurality of springs secured to the said ring and extending over the said crown pawl so as to yieldingly maintain the same in position with the laterally extending 35 teeth thereof in mesh with the laterally extending teeth of the ratchet disk whereby the laterally extending teeth of the ratchet disk slide over the laterally extending teeth of the crown pawl when the drive shaft is 40 turned in one direction during the winding and the setting of the fuse and when in the operation of the clockwork the said drive shaft turns in the opposite direction the said ratchet disk drives the crown pawl and 45 the crown pawl drives the clockwork shaft through the said pinion thereon meshing with the internal gear teeth of the crown pawl.
7. In a clockwork operated mechanical fuse, a drive shaft, a ratchet disk secured to the drive shaft and having a series of peripheral laterally extending teeth, a winding shaft, 20 a pinion thereon, a pinion on the drive shaft meshing with the pinion on the winding shaft, a crown pawl having a series of peripheral laterally extending teeth adapted to engage with the said series of 25 laterally extending teeth on the ratchet disk and also a series of internal gear teeth, a

In testimony whereof I have affixed my ⁵⁰ signature.

ANDRÉ VARAUD.
